US0D1011168S

(12) **United States Design Patent** (10) **Patent No.:** **US D1,011,168 S**
(45) **Date of Patent:** **** Jan. 16, 2024**

(54) **TORQUE TOOL**

- (71) Applicant: **Jason Chang**, Taichung (TW)
(72) Inventor: **Jason Chang**, Taichung (TW)
(73) Assignee: **JCOOL CO., LTD.**, Taichung (TW)
(**) Term: **15 Years**
(21) Appl. No.: **29/816,661**

(22) Filed: **Nov. 23, 2021**

(51) **LOC (14) Cl.** **08-05**
(52) **U.S. Cl.**
USPC **D8/85**

(58) **Field of Classification Search**
USPC D8/21-29, 82-85, 87
CPC B25B 23/0028; B25G 1/066; B25G 1/005;
B25G 1/085

(57) **CLAIM**

The ornamental design for a torque tool, as shown and described.

DESCRIPTION

FIG. 1 is a front-right-top perspective view of the torque tool, showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof;
FIG. 8 is a front-right-bottom perspective view thereof; and,
FIG. 9 is a perspective view showing the claimed design in a usage condition.
The broken lines are for the purpose of illustrating environmental structure and form no part of the claimed design.

1 Claim, 8 Drawing Sheets
